UNITED STATES PATENT OFFICE.

EMIL MILLER, OF CONCORDIA, KANSAS.

BOTTLE.

No. 838,130.

Specification of Letters Patent.

Patented Dec. 11, 1906.

Application filed July 16, 1906. Serial No. 326,462.

To all whom it may concern:

Be it known that I, EMIL MILLER, a citizen of the United States, residing at Concordia, in the county of Cloud and State of Kansas, have invented a new and useful Bottle, of which the following is a specification.

This invention has relation to bottles; and it consists in the novel construction and arrangement of its parts, as hereinafter shown and described.

The object of the invention is to provide a simple, cheap, and effective bottle which when once emptied of its contents cannot be refilled.

The bottle consists, primarily, of a closed neck having a seat located at its point of connection with the body of the bottle. A sliding stopper is retained within the neck and when the bottle is in upright position rests upon the said seat. A duct or channel extends in from the end of the neck and is slightly longer than the length of the said stopper, and when the bottle is in inverted position the said stopper moves away from the seat and passes along the said duct or channel, and the liquid which follows the stopper may pass out through the said duct or channel.

In the accompanying drawings, Figure 1 is a transverse section of the upper portion of the bottle in upright position. Fig. 2 is a transverse section of the upper portion of the bottle in inverted position. Fig. 3 is a horizontal sectional view of the bottle-neck.

The bottle 1 is provided with the neck 2, at the lower end of which is formed the seat 3. The said neck 2 is cylindrical, and its outer end is closed, as at 4. The channel or duct 5 extends in from the end of the neck 2 and is located in the inner side of the said neck. A

plurality of such channels may be provided, if desired. The stopper 6 fits snugly within the neck 2 and is adapted to slide longitudinally thereof. The said stopper 6 is cylindrical and is provided with the squared ends 7. The longitudinal axis of the stopper 6 is less than the longitudinal axis of the duct or channel 5. When the bottle is in upright position, the lower squared face of the stopper 6 rests upon the seat 3 and the bottle is sealed. When, however, the bottle is inverted, the stopper 6 is acted upon by gravity and moves toward the opposite closed end of the neck 2. When the squared ends 7 of the said stopper 6 which is located nearest the seat 3 pass below the inner end of the duct or channel 5, the liquid enters the said duct or channel and flows through the same out of the bottle.

Having described my invention, what I claim as new, and desire to secure by Letters Patent, is—

A bottle, a neck attached to the bottle, a seat formed at the point where said neck joins the bottle, a stopper slidably located in said neck, said neck having its outer end integrally closed and a channel located in its side and passing through the closed end of the neck and being longer than the longitudinal axis of the stopper, the stopper forming one of the longitudinal sides of the channel when the bottle is inverted.

In testimony that I claim the foregoing as my own I have hereto affixed my signature in the presence of two witnesses.

EMIL MILLER.
